UNITED STATES PATENT OFFICE.

JOHN J. SCHULZ, OF SOUTH SAN FRANCISCO, CALIFORNIA, ASSIGNOR TO ANNA SCHULZ, OF SOUTH SAN FRANCISCO, CALIFORNIA.

PORABLE CRANE.

1,254,282.

Specification of Letters Patent. Patented Jan. 22, 1918.

Application filed August 27, 1917. Serial No. 188,333.

To all whom it may concern:

Be it known that I, JOHN J. SCHULZ, a citizen of the United States, and a resident of South San Francisco, in the county of San Mateo, State of California, have invented certain new and useful Improvements in Portable Cranes; and I do hereby declare the following to be a full, clear, concise, and exact description of the same.

10 The invention is an improved portable crane, particularly useful in a rolling mill for conveying steel billets from one rolling machine to another. However, the invention may be used for other purposes.

15 In this specification and the annexed drawing, I illustrate my invention in the form which I consider the best, but I do not limit myself to such form because this invention may be embodied in other forms 20 and it is to be understood that in and by the claims following the description herein, I intend to cover my invention in whatever form it may be embodied.

Referring to the drawing:

25 Figure 1 is a side elevation of my improved portable crane.

Fig. 2 is a front end elevation of the upper part of the crane.

In the drawing, 1 indicates a truck comprising a base 2 and casters 3 upon which said base is mounted. On the base 2 is mounted a turntable 4, comprising a stationary member 5 secured to the base and a rotatable member 6, rotatably mounted on 35 said stationary member. On the rotatable member of the turntable is secured a standard 7 formed with a vertical slot 8. A gear 10 is journaled upon the standard 7 within the slot 8 and meshes with a gear 11 mounted within the lower part of said slot on shaft 12 suitably journaled in the standard. A gear 13 is secured on the outer end of the shaft 12 at one side of the standard 7 and meshes with an idler 14 suitably journaled 40 on the side of the standard. The idler 14 meshes with the pinion 15 on the drive shaft 16 of a motor 17 mounted on a bracket 18 secured to the side of the standard 7. The motor drives the gear 10 through the 45 medium of pinion 15, gear 14, gear 13, shaft 12 and gear 11. A carrier 20 is formed with a segment 21 which extends through the upper part of the slot 8 and has an internal segmented gear 22 thereon which meshes 55 with the upper part of gear 10 which gear

supports the carrier on the standard 7. The radius of the segmented gear 22 is greater than the radius of the gear 10 which enables the gear 10 upon rotating, to move the carrier forwardly and backwardly with relation to the standard 7 and truck 1 and enables the carrier 20 to turn upon the gear to swing the forward end of the carrier upwardly or downwardly. A roller 25 is journaled in crossheads 26 slidably mounted in vertical slots 27 in the upper part of the standard 7, which crossheads are pressed downwardly by springs 27 mounted upon said crossheads and upon brackets 28 secured to the top of the standard 7, the action of the springs maintaining the roller 25 in engagement with the upper face of the segment and holding the segmental gear 22 in tensional engagement with gear 10. The rotatable member 6 of the turntable 4 is formed with a gear 30, with which meshes a pinion 31 on shaft 32 journaled in a bearing 33 on the truck base 2. A gear 34 is secured on the shaft 32 with which meshes a pinion 35 on the shaft 36 of motor 37 which motor is mounted on the truck base 2. The standard 7 and the parts mounted thereon including the carrier are turned by the motor 37 through the medium of pinion 35, gear 34, pinion 31, and gear 30. 50 Tongs 40 are placed on the forward end of the carrier 20 for grasping and holding the billets 41 so that the carrier 20 may carry the billets from one rolling machine to another. The tongs comprise a pair of jaws 42 and 43 and arms 44 and 45 extending respectively from said jaws, the tongs being pivoted by pivot 46 to a bracket 47 depending from the forward end of the carrier 20. The jaws of the tongs are normally held 55 open by a spring 48 which bears against the inner side of the arms 44 and 45. Two cables 49 and 50 are connected to the upper ends of the arms 44 and 45 which cables pass over sheaves 51 mounted on the forward end of the carrier 20 and are connected at 52 to a cable 53. The cable 53 passes over sheaves 54 and 55 mounted on the carrier, through the slot 8 in the standard 7 and is connected to an operating lever 56 mounted on the rear end of the carrier 20. A locking means 57 is provided for locking the lever 56 at the proper position for holding the tongs 40 closed through the medium of the cables 53 and 49 and 50 so 60 65 70 75 80 85 90 95 100 105 110

that the tongs will hold the billets firmly. A weight 60 is placed on the rear end of the carrier 20 to balance the carrier.

It will be apparent that the carrier may be moved forwardly and backwardly by the motor 17, rotated horizontally by the motor 37 and swung vertically up and down about the gear 10 so that the tongs may grasp and convey the billets from one rolling machine 10 to another. The open jaws of the tongs when lowered over the billets position themselves properly for gripping the billets.

Having described my invention, I claim as new, and desire to secure by Letters Patent:

1. In a portable crane, supporting means, a gear mounted on said supporting means, a carrier, a segmental gear on said carrier, meshing with and supported by said gear, means for rotating said gear to move said carrier forwardly and backwardly.
2. In a portable crane, supporting means, a gear mounted on said supporting means, a carrier, a segmental gear on said carrier meshing with and supported by said gear, means for rotating said gear to move said carrier forwardly and backwardly, and said carrier being mounted to swing vertically about said gear.
3. In a crane, supporting means, a gear mounted on said supporting means, a carrier, a segmental gear on said carrier meshing with said gear, means for rotating said gear to move said carrier forwardly and backwardly.
4. A crane comprising supporting means, a gear mounted on said supporting means, a carrier, a segmental gear on said carrier meshing with said gear, the radius of said segmental gear being greater than the radius

of said gear to permit forward and backward movement of the carrier upon rotation of said gear and to permit swinging movement of the carrier about said gear.

5. A crane comprising a support, a gear 45 mounted on said support, a carrier, a segmental gear on said carrier meshing with said gear for moving said carrier forwardly and backwardly and for permitting vertical swinging movement of said carrier. 50

6. A portable crane, comprising supporting means, a gear mounted on said supporting means, a carrier, a segmental gear on said carrier, meshing with said gear, and a roller engaging said carrier and maintaining 55 said segmental gear in engagement with said gear.

7. In a portable crane, supporting means, a gear mounted on said supporting means, a carrier, a segmental gear on said carrier 60 meshing with said gear, means for preventing disengagement of said segmental gear and said gear, and means for rotating said gear.

8. In a portable crane, supporting means, 65 a gear mounted on said supporting means, a carrier, a segmental gear on said carrier meshing with said gear, a roller yieldingly mounted on said supporting means and engaging said carrier for preventing disengagement of said segmental gear and gear, and means for rotating said gear.

In testimony whereof, I have hereunto set my hand at San Francisco, California, this 20th day of August, 1917.

JOHN J. SCHULZ.

In presence of—

A. J. HENRY,
LINCOLN JOHNSON.
